UNITED STATES PATENT OFFICE.

JOHN A. KESSEL, OF BUFFALO, NEW YORK.

ASH-SIFTER.

1,352,667.

Specification of Letters Patent. Patented Sept. 14, 1920.

Application filed March 6, 1917. Serial No. 152,530.

To all whom it may concern:

Be it known that I, JOHN A. KESSEL, a citizen of the United States, residing at Buffalo, in the county of Erie and State of New York, have invented new and useful Improvements in Ash-Sifters, of which the following is a specification.

This invention relates to an ash sifter which permits of sifting ashes without permitting dust to escape to the surrounding atmosphere as is commonly the case in ash sifters as heretofore constructed. It is the object of this invention to produce a sifter of this character which is simple and inexpensive in construction, which can be easily operated, and which permits of conveniently separating the dust and clinkers from the good coal without removing the sieve from the sifting chamber and thereby render the sifting operation cleanly and agreeable.

In the accompanying drawings:

Figure 1 is a perspective view showing one form of ash sifter embodying my invention. Fig. 2 is a vertical section of the same taken on line 2—2, Fig. 3. Fig. 3 is a horizontal section taken on line 3—3, Fig. 2. Fig. 4 is a fragmentary vertical section taken on line 4—4, Fig. 3. Figs. 5 and 6 are perspective views of the two sections of the sieve forming part of my invention. Fig. 7 is a similar view of a scoop for use in placing the ashes to be sifted into the sieve within the sifting chamber. Fig. 8 is a vertical section of an ash sifter showing my improvements in a slightly different form from that shown in Figs. 1 and 2.

Similar characters of reference indicate corresponding parts throughout the several views.

In the form of my invention shown in Figs. 1 and 2, the sifting chamber is formed within an inclosing casing which preferably comprises an upright cylindrical wall 1 having an open top, and a cover 2 adapted to close this top, both of these members being preferably constructed of sheet metal in any suitable manner. The outer side of the sifting chamber may be provided with handles 1^a for carrying the same and the cover 50 may be provided with a handle 2^a for lifting it. Within the lower part of this sifting chamber the wall is provided with an internal support which preferably comprises a plurality of inwardly projecting supporting lugs or brackets 3 arranged at different points in the circumference of this wall.

On this support a sieve is adapted to be mounted so that the same can be oscillated horizontally for the purpose of separating the ashes which are placed in the sieve and cause the dust to pass downwardly below the same while retaining the large particles therein. This sieve may be variously constructed but in its preferred form the same is generally of circular or cylindrical shape and comprises a cylindrical upright frame or rim 4 which rests with its underside on the supporting lugs 3 and a partition 5 extending across the space within the sieve frame on one side of its center or axis of rotation so as to form two compartments in this frame one of which is comparatively large and the other comparatively small. A large main screen section 6 is permanently secured to the lower end of the large compartment of the sieve frame and a small auxiliary screen section 7 is removably arranged in the small compartment of the sieve frame and adapted to rest on lugs or shoulders 8 formed on the sieve frame with in the small compartment thereof. If desired the small sieve section may be provided with a rim 9 for stiffening the same and also with a handle 10 secured centrally to its upper side for the purpose of removing it from the sieve frame when required. The sieve as a whole may be introduced into the sifting chamber from its top and also removed therefrom by means of handles 11, 11 secured to the peripheral wall thereof on its diametrically opposite sides, as shown in Figs. 2, 3 and 6. The horizontally oscillating or shaking movement is imparted to the sieve by means of a handle 12 projecting through a horizontal slot 13 in the side wall of the sifting chamber and connected at its inner end to the main frame or wall of the sieve. This handle is made detachable from the sieve frame in order to permit the latter to be removed from the sifting chamber for dumping the good coal out of the sieve. This detachable connection may be constructed in various ways, for instance, by providing the inner end of the shaker handle with an externally screw threaded shank 14 engaging with a screw threaded opening or socket 15 in the wall of the sieve frame, as shown in Figs. 3, 4 and 6. Upon shaking the sieve the dust passes downwardly from the underside thereof while the large particles, such as the good coal and clinkers, are retained within the main and auxiliary

sieve sections. In order to permit of conveniently removing the clinkers from the good coal the auxiliary sieve section is lifted out of the small compartment of the sieve frame 5 after which the clinkers may be removed from the coal within the main and auxiliary sieve sections and dropped through the space between the partition of the screen frame and the wall of the sifting chamber 10 and into the dust receptacle below the sieve. The partition of the screen therefore produces a flattening on one side of the main sieve section which provides the necessary passage through which the clinkers may be 15 removed from the good coal and thrown into the dust pile below without necessitating removing the sieve from the sifting chamber.

Means are provided whereby the ashes to 20 be sifted may be introduced into the sifting chamber and deposited within the sieve without producing any appreciable dust outside of the sifting apparatus. For this purpose the sifting chamber is provided on 25 one side of its wall with a laterally projecting hood 16 which is preferably of rectangular form and provided at its outer end with an ash inlet opening 17. This opening is surrounded by a flange 18 which inclines 30 from its upper end inwardly toward its lower end so as to form a seat 19 on the inner side of this flange which is adapted to be engaged by a vertically swinging gate, valve or shutter 20. This shutter is pivoted 35 at its upper end on the inner side of the hood, as shown at 21 and is held normally by gravity in its closed position against the seat around the inlet of the hood.

The ashes are preferably removed from 40 the ash pit of a furnace, stove or other place and passed through the inlet of the sifting chamber and deposited upon the sieve therein by means of a scoop 22 which is of cylindrical form and provided with an inclined 45 front end and the handle 23 at its rear end. As the front end of this scoop enters the inlet of the sifting chamber it engages with the shutter and pushes the same inwardly into an open position, as indicated by dotted 50 lines in Fig. 2, and upon withdrawing this scoop after depositing the ashes on the sieve the weight of the shutter automatically returns the same to its closed position, as indicated by full lines in Fig. 2, thereby effectively preventing the escape of any dust 55 from the interior of the sifting chamber to the surrounding atmosphere.

During the operation of sifting the ashes there is no tendency of any of the dust to 60 escape through the slot 13 in the side wall of the sifting chamber because there is no air current through this opening and for the further reason that this slot is practically covered by the annular frame of the 65 sieve, as shown in Figs. 1, 3 and 4.

As the dust drops from the underside of the sieve the same may be taken care of in any suitable manner and received either in a refuse receptacle or can 24 which is separate from the sifting apparatus proper, as 70 shown in Figs. 1 and 2, or in a receptacle 25 which is formed in one piece with the wall 26 of the sifting chamber, as shown in Fig. 8. When the sifting chamber is made separate from the refuse receptacle the lower 75 end of the wall of the sifting chamber is provided with an annular base flange 27 whereby the same may rest either upon the ground or floor when the sifting apparatus is not in use, or the same may rest upon the upper edge of and form a tight joint with 80 an ash receptacle which is of the proper size to fit the lower edge of the base flange, as shown in Fig. 2.

In order, however, to permit this sifting apparatus to be used in connection with ash cans or refuse receptacles which are of smaller diameter the interior of the sifting chamber is provided below the sieve with a downwardly tapering conical guide 28 90 which latter may be supported with its underside on the upper edge of an ash can or receptacle of smaller diameter, such a can 29 being shown by dotted lines in Fig. 2. The base flange of the sifter preferably extends downwardly below the lower end of the guide 28 so that the latter will not be injured when the base flange rests on the floor. By this construction of ash sifter the same may be used in connection with any 95 available can or receptacle for receiving the dust and clinkers and the same may be removed therefrom before the ash man carts away the can, thereby avoiding injury to the ash sifter. 100

When the ash receptacle is made in one piece with the sifting chamber, as shown in Fig. 8, the ashes may be removed therefrom into another receptacle which is to be handled by the ash man in order to avoid damage to the sifting apparatus. 105

Owing to the dust resulting from this sifting operation being positively confined within the sifting chamber in this apparatus it permits this operation to be performed in 110 the basement or other available place of a building without causing any objectionable spreading of dust into the surrounding space, thereby rendering the operation of sifting the ashes more sanitary, pleasant and 115 convenient. 120

Moreover, this ash sifter has no delicate parts which are liable to get out of order and owing to the simplicity of its construction the same can be produced at comparatively low cost. 125

I claim as my invention:

1. An ash sifter comprising a cylindrical sifting chamber having its axis arranged vertically and provided with internal sup- 130

ports, and a circular sieve adapted to rest on said supports and to oscillate horizontally thereon and having a part of its side flattened to form a space between the sieve and the wall of the sifting chamber.

5 2. An ash sifter comprising a cylindrical sifting chamber having its axis arranged vertically and provided with internal supports, and a circular sieve adapted to rest 10 on said supports and to oscillate horizontally thereon and having a large main section and a small auxiliary section, the division between said sections being on one side of the center of the axis of the sieve.

15 3. An ash sifter comprising a sifting

chamber containing an internal support, and a sieve engaging said support and having a frame, a main screen section permanently connected with said frame, and an auxiliary screen section detachably mounted on said 20 frame.

4. An ash sifter comprising a sifting chamber containing an internal support, and a sieve engaging said support and having a frame, a comparatively large screen section 25 permanently connected with said frame, and a comparatively small screen section detachably mounted on said frame.

JOHN A. KESSEL.
